[57] CLAIM

The ornamental design for a fob style vest pocket pager, as shown and described.

DESCRIPTION

FIG. 1 is a front elevational view of the fob style vest pocket pager showing my new design, the LED readout illustration of "12:00" and "2-07" being for illustrative purposes only and forming no part of the claimed design;

FIG. 2 is a rear elevational view thereof;

FIG. 3 is a right side view thereof;

FIG. 4 is a left side view thereof;

FIG. 5 is a top plan view thereof; and,

FIG. 6 is a bottom plan view thereof.
